UNITED STATES PATENT OFFICE.

EDWIN S. WOODS, OF CHICAGO, ILLINOIS.

ANTIFRICTION-BEARING.

979,727.

Specification of Letters Patent. Patented Dec. 27, 1910.

Application filed January 6, 1909. Serial No. 470,982.

To all whom it may concern:

Be it known that I, EDWIN S. Woods, a citizen of the United States, and a resident of Chicago, in the county of Cook and State of Illinois, have invented certain new and useful Improvements in Antifriction-Bearings; and I do hereby declare that the following is a full, clear, and exact description thereof, reference being had to the accompanying drawings, and to the letters of reference marked thereon, which form a part of this specification.

This invention relates to improvements in antifriction bearings for railway cars, and for generally similar uses, and the invention consists in the matters hereinafter set forth and more particularly pointed out in the appended claims.

My invention is herein shown as applied to a side bearing for railway cars, arranged to be applied between the truck and body bolsters, and certain features of my improvements are especially adaptable to bearings for this purpose. Certain features of the invention may be applied to other forms of bearings. The following specific description of the side bearing herein illustrated is not intended to impose limitations with respect to the structural details of the device or its application or use.

In the drawings:—Figure 1 is a longitudinal section of a side bearing for railway cars embodying my invention. Fig. 2 is a top plan view of the bearing. Fig. 3 is an end view thereof, partially broken away. Fig. 4 is an end view of a modification of the bearing. Fig. 5 is a fragmentary perspective view, illustrating one of the tracks for supporting the antifriction element when out of contact with the upper and lower bearing members. Fig. 6 is an axial section of an antifriction element which may be employed in said bearing.

The side bearing shown in the drawing embraces, in general terms, a casing or carrier 10 which is formed to provide an elongated chamber 11 to receive an antifriction element, herein shown as consisting of a roller 12 which is capable of rolling endwise of said chamber. The said roller is provided at its ends with end bearings or trunnions 14 and the carrier is provided at its side walls with elongated channels 15 to receive said trunnions. The lower walls of said channels are formed by generally horizontal flanges 16 which extend inwardly from the

lower margins of the side walls of the carrier. Said flanges constitute tracks on which the trunnions rest and roll when the roller is free from the upper and lower bearing surfaces, whereby the roller may be returned to a central or other position in the carrier, as common in this type of bearing. The illustrated arrangement of centering the roller is like that shown in my pending application for U. S. Letters Patent, Serial Number 417,275, filed on the 24th day of February 1908.

The carrier is attached to its support, as the body bolster of a car, by means of suitably located lugs 18, 18 extending laterally from the top wall thereof which are apertured to receive fastening bolts. The upper bearing member for the roller consists, as shown in Figs. 1 to 3 inclusive, of a steel wear plate 20 which is fitted to the lower side of the top wall of the carrier and which may be fixed in the carrier in any suitable manner. Rivets 21 are shown as fixing said wear plate to the top wall of the carrier. The lower bearing member for the roller is indicated by the line 22 which, in a side bearing, usually consists of a flat plate attached to the truck bolster below the body bolster. In some instances the upper bearing member for the roller may consist of the lower side 23 of the upper wall of the carrier.

The carrier may be made of two parts or halves 25, 26 which are joined by means of flat fitting lugs 27, 28 extending laterally from the walls of the carrier and the two parts of the carrier may be fastened together by bolts or rivets 29 extending through apertures in said lugs. As herein shown, the carrier consists of upper and lower members 25 and 26, respectively, which are joined in a horizontal plane. The lugs 27 and 28, by which said upper and lower members are attached together, extend laterally from the side walls of the carrier. As herein shown, the lugs 27 of the upper member are formed on short, laterally extending flanges 30, 30 of the side walls, and the members of the casing are joined in such manner that said flanges 30 constitute the upper walls of the trunnion receiving channels 15, the side and bottom walls of which channels are formed by the side walls of the lower member and the track flanges 16, respectively. The form of the carrier members thus described permits said members to be made

of drop forgings and also enables the same to be assembled to provide the required internal contour to conveniently produce the trunnion channels. The lugs 27 and 28 by which the upper and lower members of the carrier are joined together obviously serve to greatly stiffen the walls of the built up carrier.

The carrier is open at its ends, the end walls, or at least one of them, being omitted and the channels extend entirely to the open end or ends of the carrier. This arrangement permits the roller to be introduced into and removed from the chamber 11 through the open end of the carrier. In the construction shown in Figs. 1 to 3, the roller is locked from displacement in the carrier by the combined action of the wear plate 20 and lugs 35, 35 rising from the ends of the track flanges. Said lugs extend above the level of the upper faces of the track flanges such distance that when the wear plate is in place the trunnions of the roller will not pass over the lugs. When the wear plate is removed, however, the distance between the upper faces of the lugs and the top wall of the casing is greater than the distance between the top of the roller and the lower sides of the trunnions, whereby the roller may be readily inserted into and removed from the chamber. After the roller has been thus inserted, the wear plate is introduced into the chamber and fixed to the carrier in any suitable manner, and the presence of the wear plate serves to hold the roller from displacement as stated. The lugs 35 serve as stops to arrest the roller at the limits of its rolling movement in the carrier.

In the construction shown in Fig. 4, where the wear plate, as a separate element, is omitted there are provided at one or both ends of the carrier stops 36 which are located in the path of the trunnions above the track flanges 16 and serve, not only as means to arrest the roller, but also as means for locking the roller from displacement in the carrier. The said stop 36, as herein shown, consists of the heads of bolts 37 which extend through the side walls of the carrier and said bolts are fixed in place by nuts 38 which are screw-threaded on the outer ends of the bolts.

I may provide the tracks at or near their longitudinal centers thereof with depressions 40, as indicated in Fig. 5, arranged to receive the trunnions of the roller when the roller is at its central position. The presence of said depressions in the tracks serve to stop the roller at its central, or other desired position relatively to the tracks when relieved from the load, and thus insure that the roller, when next engaged with the upper and lower bearing members, will start from a given or predetermined posi-

tion in the carrier and that it will not be thrown beyond its centering position at such time by reason of sudden shocks, due to throwing the brakes on the car, or for other reason. As a further or separate improvement, the roller 12, for this and other bearing devices, may be made up of a number of disks or members 42, 43 which are relatively rotative about a common axis. As shown in Figs. 3, 4 and 5 the roller is made up of three of such members, the two outer members 42 being provided with the end bearings or trunnions 14 and the central member being confined between the outer members. By reason of the close confinement of the roller laterally in the carrier no special means need be employed for holding the disks or members of the roller together, and when used in such relation to the carrier, the said disks or members may be merely interlocked to avoid axial displacement. For this purpose the central member or disk 43 may be provided with suitable axial projections 45 arranged to enter similarly formed recesses in the proximate faces of the outer disks or members 42.

The construction and arrangement of the roller in the manner described enables me to employ a roller having a cylindric or parti-cylindric periphery while almost entirely avoiding the sliding friction of the roller on the bearing members due to the uses of such cylindric roller in the relation herein referred to, that is, wherein the carrier of the roller swings on the arc of a circle, which in a side bearing is struck from the axis of oscillation of the car body bolster. Theoretically, in order to avoid such sliding friction when using a solid roller or other antifriction element, the bearing surface thereof should be made conical. An objection to a conical roller or antifriction element in this relation, however, is its end thrust against the wall of the carrier adjacent to the larger end of the roller. By using a roller made up of a number of parts which are free to rotate relatively to one another, I am enabled to employ a roller having a cylindric periphery and thereby avoid such end thrust.

I claim as my invention,—

1. In an anti-friction bearing, upper and lower bearing members, an interposed anti-friction element having a cylindric surface, said anti-friction element embracing a plurality of disks or members arranged flatwise together and rotative relatively to each other, and interlocking means on said element members arranged to avoid axial displacement thereof.

2. A side bearing for railway cars and the like, comprising a carrier arranged to form a chamber for an anti-friction element and provided with means for attaching it to a support, and an anti-friction element

in said chamber, the anti-friction element embracing a plurality of disks or members arranged with their flat sides together and rotative relatively to each other, the outer-
5 most of said members being provided with end bearings or trunnions.

In testimony, that I claim the foregoing

as my invention I affix my signature in the presence of two witnesses, this 2nd day of January A. D. 1909.
